PERCUSSION-FUSE.

1,108,819.

Specification of Letters Patent.

Patented Aug. 25, 1914.

Application filed March 7, 1913. Serial No. 752,670.

To all whom it may concern:

Be it known that I, KARL WIESER, residing at Bredeney, Germany, a subject of the Emperor of Germany, have invented a certain new and useful Improvement in Percussion-Fuses, of which the following is a specification.

The present invention relates to a new and particular percussion fuse provided with a retarding mechanism to be thrown into and out of operation.

In the drawing is shown, as a constructional example of the subject matter of the invention, a base fuse which acts automatically either with or without retardation, according as the violence of the impact is greater or less.

In Figures 1 and 2 two axial longitudinal sections of the fuse are represented, each showing certain parts of the fuse in different position.

The fuse casing A which is closed in front by a plug screw a^1 , carries a striker B, containing the primer and adapted to move in the direction of the plug screw a^1 when the projectile strikes upon the target. The striker is prevented from moving, when the shot is fired, by a safety device C acting under centrifugal action and of any known construction.

The primer consists of two priming charges b^1 and b^2 of different kind and placed one behind the other. The front priming charge b^1 , is made from a retarding composition, which when ignited by a firing pin burns away slowly without explosion, but which explodes, when strongly ignited by a powerful jet of flame. The well known retarding compositions are composed of a pellet of black powder and a pellet of fulminate of mercury, lying in front of the black powder pellet produces a small igniting effect only. A retarding composition of the same properties, but which represents a homogeneous mass, is obtained in a simple manner by adding, to the ingredients of the well known black powder retarding pellets (salt peter, sulfur, coal), a small quantity of chlorate of potash (up to 5%). The sensitivity of the pellet for impact is thus increased. The following composition, therefore, is suitable for a retarding pellet of the desired kind: salt peter: 70%; sulfur: 12%; coal: 14%; chlorate of potash: 4%.

The second priming charge, b^2 , is of such

a composition (for example fulminate of mercury) that it explodes both when ignited by a firing pin and when subjected to the action of an igniting flame. In front of the striker B there is arranged in the fuse casing A a partition wall a^2 .

Against the end face of the partition wall a^2 remote from the striker B bears a second striker D which moves in the same direction as the striker B. The striker D is prevented from moving by a compressible ring E, the axis of which coincides with the longitudinal axis of the fuse. The strength of this ring is so adjusted that it can only be compressed by the striker D (see Fig. 2), when the projectile strikes against a very resisting target such as an armor plate for example, but when the projectile strikes against a body which offers but little resistance, it does not appreciably change its shape so that the striker D remains in its original position (see Fig. 1). The striker D on which is mounted the firing pin a^3 which passes through an opening a^4 in the partition wall a^2 , has in its center a passage a^5 running in axial direction. This passage communicates on the one hand, through the medium of the opening a^4 in the partition wall a^2 , with the space in which the jet of flame is produced, and on the other hand, through the medium of a hole a^6 provided in the plug screw a^1 with the percussion charge F which is arranged in the plug screw a^1 .

The length of the firing pin a^3 is so proportioned, that when the projectile strikes and the striker B is shot forward thereby, the firing pin can penetrate right up to the rear priming charge b^2 when the striker D remains in its original position (see Fig. 1), but can only ignite the front slowly burning priming charge b^1 , when the striker D shoots forward, with the simultaneous compression of the ring E.

The action of the fuse is as follows: When the projectile strikes against a target which offers but little resistance the striker B only shoots forward, while the striker D remains in practically its original position, owing to the resistance of the ring E (see Fig. 1). The firing pin a^3 therefore penetrates right up to the rear priming charge b^2 , which immediately explodes and simultaneously causes the priming charge b^1 to explode also. The jet of flame so produced passes without any retardation along the

course a^3 , d^2 , a^4 to the percussion charge F . If on the other hand the projectile strikes against a resisting target, the striker D shoots forward also under the influence of 5 the violent shock, overcoming the resistance of the ring E as it does so. In this case (see Fig. 2) the firing pin d^1 can only penetrate into the front priming charge b^1 , which, in this case, burns away slowly. Only after 10 this priming charge has almost completely burnt out, that is to say after the expiration of a definite time, is the rear priming charge b^2 caused to explode by the flame of the burning priming charge b^1 , and only now 15 does the ignition of the percussion charge F take place, by the flame issuing from the priming charge b^2 . The fuse therefore acts with retardation.

I claim:

20 1. A combination fuse for quick and delayed action, having a self adjusting firing pin, a primer and a striker; said striker moving on impact of the projectile, thereby, 25 in coöperation with said firing pin, causing the ignition of said primer, said primer comprising two pellets one behind the other, the one pellet consisting of a slow burning composition and the other pellet consisting of quick match, the position of said firing pin 30 varying in accordance with the resistance of the target, whereby the firing pin in one case ignites one of said pellets and in the other case ignites both pellets.

2. A combination fuse for quick and delayed action, having a self adjusting firing pin, a primer and a striker; said striker moving on impact of the projectile, thereby, 35 in coöperation with said firing pin causing the ignition of said primer comprising two pellets one behind the other, the one pellet nearest to the firing pin consisting of a slow burning composition and the other pellet remotest from the firing pin consisting of quick match; said firing pin after an impact 40 of the projectile with a target of great resistance, having such a position that it can reach only the slow burning pellet, and the firing pin after an impact of the projectile 45 with a target of slight resistance having such a position that it will reach the quick burning pellet.

3. A combination fuse for quick and delayed action, having a self-adjusting firing pin, a primer, two strikers and a housing 55 therefor; both of said strikers being in alignment; and one of the strikers carrying said firing pin and the other striker carrying said primer; said primer comprising two pellets one behind the other, the pellet 60 nearest the firing pin consisting of a slow burning composition and the other pellet consisting of quick match; a yielding member interposed between the wall of said housing and one of said strikers, said yielding member constructed to withstand the

blow of impact with a target of slight resistance, but constructed to collapse through the movement of said strikers on the impact with a target of great resistance, whereby said firing pin will penetrate both of said 70 pellets causing quick action in the first instance, but will penetrate only the slow burning pellet causing delayed action of the fuse in the second instance.

4. A combination fuse for quick and delayed action, having an impact member carrying a firing pin, another impact member carrying a primer, said impact members being arranged one behind the other and the rear one adapted to move on impact of the 75 projectile, thereby causing said firing pin to ignite the primer, said primer comprising two priming charges one behind the other, the one priming charge lying next 80 said firing pin consisting of a composition adapted to burn away slowly without explosion when ignited by said firing pin on impact, but to explode when ignited by a powerful jet of flame, and the other priming charge consisting of a quick match; and 85 means for holding said impact members in a variable distance from another at the end of the movement of said rear impact member, whereby the firing pin according to 90 the quantity of said distance may ignite either said first-named priming charge only or both priming charges.

5. A combination fuse for quick and delayed action, having an impact member carrying a firing pin, another impact member 100 carrying a primer, said impact members being arranged one behind the other and the rear one adapted to move on impact of the projectile, thereby causing said firing pin to ignite the primer, said primer comprising two priming charges one behind the other, the one priming charge lying next 105 said firing pin consisting of a homogeneous mass adapted to burn away slowly without explosion when ignited by said firing pin on impact, but to explode when ignited by a powerful jet of flame, and the other priming charge consisting of a quick match; and means for holding said impact members in a variable distance from another at the end 110 of the movement of said rear impact member, whereby the firing pin according to the quantity of said distance may ignite either 115 said first-named priming charge only or both priming charges.

6. A combination fuse for self adjusting quick and delayed action, having an impact member carrying a firing pin, another impact member carrying a primer, said impact members being arranged one behind the other and adapted to move both forward on impact of the projectile, thereby causing said firing pin to ignite the primer, said primer comprising two priming charges one 125 behind the other, the one priming charge 130

lying next said firing pin consisting of a composition adapted to burn away slowly without explosion when ignited by a powerful jet of flame, and the other priming charge consisting of a quick match; and means for holding the forward impact member at the end of its forward movement in a position varying in accordance with the resistance of the target, whereby the firing

pin may ignite either said first-named priming charge only or both priming charges.

The foregoing specification signed at Barmen, Germany, this 14th day of February, 1913.

KARL WIESER. [i.s.]
